Primary Examiner — Shawn T Gingrich*Assistant Examiner* — Bryan N. Melvin(57) **CLAIM**

The ornamental design for a charging base, as shown and described.

DESCRIPTION

The file of this patent contains at least one drawing/photograph executed in color. Copies of this patent with color drawing(s)/photograph(s) will be provided by the Office upon request and payment of the necessary fee.

1. Charging base

1.1 is a front view of a charging base according to the present design;

1.2 is a rear view thereof;

1.3 is a left side view thereof;

1.4 is a right side view thereof;

1.5 is a top plan view thereof;

1.6 is a bottom plan view thereof;

1.7 is a perspective view thereof; and

1.8 is another perspective view thereof.

The portion shown in red color illustrate portions of the charging base that form no part of the claimed design.
